UNITED STATES PATENT OFFICE.

VERNON J. HARWARD AND WALTER P. BUDD, OF DURHAM, NORTH CAROLINA.

ROOFING CLIP.

Application filed July 12, 1923. Serial No. 651,184.

To all whom it may concern:

Be it known that we, **VERNON J. HARWARD** and **WALTER P. BUDD**, citizens of the United States, residing at Durham, in the county of Durham and State of North Carolina, have invented certain new and useful Improvements in Roofing Clips, of which the following is a specification.

This invention relates to improvements in 10 roofing clips.

The primary object of this invention is the provision of a roofing clip which is adapted for use in connection with the effective placing of shingles or composition roofing. 15

A further object of this invention is the provision of a practical type of roofing clip embodying a structure which will permit of its performing its main function, that of 20 maintaining the shingle or roofing effectively upon the roof, and embodying an additional function in that the same will permit of relative movement of the pieces of roofing material, which is mainly important 25 in shingle types of roofing, in that, incident to temperature variations the roof structure may shrink or the shingles or roofing expand or contract.

A further object of this invention is the provision of a roofing clip of the above 30 mentioned character, substantially identical with the type of roofing clip shown in our copending application, Serial No. 638,-965, filed May 14, 1923, and embodying 35 material improvements thereover, in that the same will permit of contraction and expansion of the roofing materials or the roof upon which it is placed without sacrificing any of its inherent advantages.

40 Other objects and advantages of this invention will be apparent during the course of the following detailed description.

In the accompanying drawing, forming 45 a part of this specification, and wherein similar reference characters designate corresponding parts thruout the several views,

Figure 1 is a plan view of a roof, showing composition roofing shingles as placed thereon in cooperative relation with the improved clip herein set forth.

50 Figure 2 is a fragmentary cross sectional view, taken substantially on the line 2--2 of Figure 1, and showing the manner in which the improved clips are connected to the shingles and to the roof.

55 Figure 3 is a fragmentary cross sectional

view, taken through an improved clip, showing the manner in which the same is cooperatively used in connection with shingles, prior to its final placement thereon. 60

Figure 4 is a perspective view of the preferred form of the improved shingle clip, this form of the invention being constructed of sheet material, such as zinc, tin, or galvanized metal. 65

Figure 5 is a perspective view of a modified form of this invention, preferably constructed after the invention from wire.

In the drawing, wherein for the purpose of illustration are shown preferred and modified forms of this invention, the letter A may generally designate the preferred form of clip, which may be used in connection with the placement of sheets of roofing material B upon the roofing structure C. 70 75

In lieu of the form of invention A, a clip F may be used, which has some advantages over the formation of the improved clip out of sheet material.

Referring to the improved and preferred 80 form of clip A, the same while preferably constructed of zinc, tin or other galvanized sheet material may be made of any material. It preferably includes a flat or plane elongated attaching portion 10; which adjacent 85 one end edge 11 thereof is preferably provided with a nail or fastener inserting opening 12; the opening 12 being continued longitudinally of the attaching portion 10, in a reduced slot or extension 13, contiguous 90 with the opening 12 and extending toward the free edge 11. The opening 12 together with the reduced elongated extension 13 thereof preferably forms a slot which extends longitudinally of the attaching portion 95 10, adjacent one end thereof. At the other end of the attaching portion 10, an arcuate front or connecting portion 15 is provided, which is integral with the attaching flat portion 10, and has also a retaining 100 tab portion 16 formed integral therewith. The retaining tab 16, after the clip A has been manufactured, but before its application upon a roof, for the major run thereof, is preferably plane and is disposed in acute angular relation with respect to the plane of the attaching portion 10; being connected to said attaching portion 10, as by the heretofore mentioned arcuate front portion 15. At the free end, the retaining tab 16 is bent 110 downwardly, as at 17, in effect providing a flange or hook which, while of relatively

short plane formation may be arcuate; it being most important that the same faces toward the plane of the attaching portion 10, and of course being bent transversely 5 to the plane of said attaching portion 10, and preferably in acute angular relation with respect to the plane of said angular portion 10.

Referring to the application of the improved clip A upon a roof C, the shingles D 10 are placed upon each other and upon the roof C according to the alignment which they will assume by reason of positioning of the clips A. The clips A are placed substantially upon the roofing structure C, according to the instructions contained in our co-pending application, above referred to. To this end, the clips A are placed just rearwardly of the slot 25 between the shingle 15 stubs 26 of the composition shingles B so that the front edge of the clip A, as defined by the outer surface of the arcuate connecting portion 15 aligns substantially with the end edge 27 of a slot 25. The attaching portion 10 of a clip A so placed is then secured to the shingle B upon which it is placed and to the roof C substantially as is illustrated in the drawings, and as set forth in our co-pending application above referred to. The 20 superposed rows of shingles B are accurately aligned by placing the lower edges 29 of the shingle stub 26 thereof within the pockets provided intermediate the attaching portion 10 and retaining tab 16 of the clips A. This, 25 of course, insures that the shingles will have all of the shingle stubs 26 thereof exposed for the same depth, which is essential to a 30 uniformity of appearance.

After the improved clip A has been assembled with a superposed shingle or roofing cleat B therein, and preparatory to the final operation, the improved shingle clip A will be placed substantially as is illustrated in the full cross sectional lines in Figure 3 of the drawing. In this position, the hook end 17 of the upper retaining tab 16 will lie over the top surface of the uppermost roofing shingle. The roofer, by simply hitting the retaining tab 16 a light blow with a hammer, will flatten the retaining tab 16 over the top surface of the roofing piece B being applied, and in abutting relation therewith. During this flattening operation, the hook piece or flange 17 of the retaining tab 16 will first engage the roofing piece B and grip therein, and as the force of the hammer is fully applied, it will kick the arcuate front portion 15 of the roofing clip A outwardly from the front edge 29 of the shingle butt 26 which it receives, so that as is illustrated in dotted lines in Figure 3 of the drawings, the forward edge 29 of the shingle butt would be in considerable spaced relation with the arcuate front portion 15 of the clip A. This space 30 permits the shingle B and more

particularly the butt portions 26 thereof to expand, to decrease the space 30 so that the shingle will not buckle transversely. It is the common fault of all roofing clips which are attached to the lower end of the shingle 70 that the same will not permit the shingle to expand. However, with the improved clip A, the shingle or roofing pieces B may be assembled upon the roofing structure in facile manner, and in proper alignment principally by means of the clip A; said clips during the final placing movement thereof being automatically extended to permit of expansion and contraction of the shingles. The elongation of the openings in the attaching piece or portion 10 of the clip A also permits the clip A to slide relative to the shank 35 of the attaching element 36 of said clip A. 75

Referring to the modified form of clip as is illustrated in Figure 5, the same is preferably constructed of wire, bent intermediate its ends to provide a loop portion 40 defining an elongated opening 41 therein. Side arms 42 and 43 are bent from the loop portion 40 into substantially parallel relation and at each side of the loop portion 40; said arms 42 and 43 preferably lying in the same plane with the loop portion 40. At their free ends, and opposite the loop 40, the arms 42 and 43 are arcuated, as at 44 and 45 respectively, providing retaining extensions 46 and 47 respectively, which correspond to the retaining tab 16 of the preferred form of clip A. At their free ends the retaining portions 46 and 47 of the arms 42 and 43 are downturned, as at 48 and 49 respectively, transversely to the run of the arms 42 and 43. The planes defined by the arms 42 and 43 with their upturned retaining portions 45 and 46 are transversely to the planes in which the arms 42 and 43 and the loop 40 lie. The application of the modified form of clip F to a roof structure is analogous to that above described, the hammering operation upon the retaining portions 46 and 47 tending to kick the same downwardly of the shingle being placed, so that the shingle may expand or contract without liability of buckling or stretching. 105

From the foregoing description of this invention, it is apparent that an improved roofing clip has been provided, which is adapted to effectively place and maintain roofing shingles or pieces upon a roof structure without crowding the lower edge of the superposed shingle. Very often several lines or rows of clips are placed upon the same roofing board. The roofing board, subsequent to placing of the roofing, in a good many instances shrinks transversely of the run of the board, which of course buckles the roofing. However, the slotted arrangement of the attaching tab of the roofing clip, and the retaining tab structure of the same, 110 115 120 125 130

will permit of this shrinking of the roofing board and expansion or contraction of the shingles, without liability of buckling or stretching of the shingles or roofing pieces.

- 5 It provides a very flexible roofing structure. Various changes in the shape, size and arrangement of parts, may be made to the form of invention herein shown and described, without departing from the spirit of 10 the invention or the scope of the claims.

We claim:

1. A roofing clip comprising an attaching portion, and a retaining tab bent over said attaching portion, said retaining tab 15 having the free end thereof provided with a blunt edge turned toward the attaching portion.

2. A roofing clip comprising an attaching portion, and a retaining tab bent over 20 said attaching portion and at its free end having a blunt edged flange bent in acute angular relation toward the plane of said attaching portion.

3. A roofing clip comprising an attaching portion, a retaining tab, an arcuate front portion connected to said attaching portion and retaining tab, said retaining tab having the free end thereof provided with a blunt edge turned toward the plane of said attaching portion.

4. A roofing clip comprising an attaching portion, and a retaining tab formed on an end of said attaching portion bent over said attaching portion and at its free end having 35 a blunt edge turned toward the attaching portion, said attaching portion at its other end having an elongated slot therein.

5. As an article of manufacture, a roofing clip formed of a strip of sheet material of 40 uniform width from end to end, said strip at one end thereof being bent to provide a plane attaching portion and at the other end an overturned retaining tab relatively shorter than said attaching portion connected integrally therewith by an arcuate front portion, said retaining tab at its free 45 end being downturned in acute angular re-

lation toward the plane of said attaching portion and providing a blunt edge facing the attaching portion, said attaching portion adjacent its free marginal end being provided with an opening and a reduced slot extending in communicating relation from said opening toward said free marginal end of said attaching portion. 55

6. As an article of manufacture a roofing clip for the securing of roofing to a roof structure formed of material bent to provide an attaching portion adapted to be secured to the roof structure and a retaining tab connected with one end of the attaching portion by an arcuate portion and extending over the attaching portion in spaced relation therewith for receiving between the tab and attaching portion an edge portion 60 of the roofing, said retaining tab having its free end extending towards the attaching portion for engaging the roofing and bracing the tab against movement towards the free end of the attaching portion whereby 65 when the tab is forced into flat engagement with the roofing, the arcuate portion connecting the attaching portion and retaining tab will move away from the edge of the roofing upon continued application of force 70 75 and provide a space into which the roofing may expand.

7. As an article of manufacture a roofing clip for securing roofing on a roof structure comprising a roof attaching portion having an overbent retaining tab on an end thereof, the roofing at an edge portion adapted to be received in the space between the attaching portion and retaining tab, said retaining tab at its free end being blunt and acutely inclined to the roofing so that when hit it will engage the roofing in a fixed-non-penetrating manner to permit the place of juncture of the retaining tab and attaching portion to move away from the edge of the roof providing a space into which the roofing may 80 85 90 expand.
